UNITED STATES PATENT OFFICE

160,667

COMBINATION GLASS RETAINER AND
SPOON HOLDER

Viola M. Sengstack, Washington, D. C.

Application January 25, 1950, Serial No. 7,457

Term of patent 7 years

(Cl. D44—10)

To all whom it may concern:

Be it known that I, Viola M. Sengstack, a citizen of the United States, residing at Washington, D. C., have invented a new, original, and ornamental Design for a Combination Glass Retainer and Spoon Holder, of which the following is a specification, reference being had to the accompanying drawing, forming part thereof.

Figure 1 is the top plan view of a combination glass retainer and spoon holder showing my new design;

Figure 2 is a side elevational view; and

Figure 3 is a bottom plan view thereof.

I claim:

The ornamental design for a combination glass retainer and spoon holder, as shown.

VIOLA M. SENGSTACK.
